UNITED STATES PATENT OFFICE.

CHARLES JOSEPH ROUX, OF PARIS, FRANCE.

APPARATUS FOR CONSUMING SMOKE IN STOVES AND FURNACES.

No. 858,106.

Specification of Letters Patent.

Patented June 25, 1907.

Application filed October 14, 1904. Serial No. 228,419.

To all whom it may concern:

Be it known that I, CHARLES JOSEPH ROUX, of 12 Rue Doudeauville, in the city of Paris, Republic of France, mechanician, have 5 invented Improvements Relating to Apparatus for Consuming Smoke in Stoves and Furnaces, of which the following is a full, clear, and exact description.

This invention has reference to apparatus 10 for consuming smoke in stoves and furnaces and is applicable to domestic and industrial heating apparatus of all kinds. By its means complete combustion may be obtained and consequently absolute consumption of 15 smoke, whatever the nature of the fuel employed may be, as soon as normal conditions have been established, even with the softest coals.

According to this invention the improved 20 apparatus consists broadly of a furnace with double walls, between which is left a vacant space opening at its upper part into the furnace and conducting the gases and smoke to a second combustion center, and one or more 25 openings formed in the inner wall of the furnace at the level of the incandescent zone of the fuel and permitting of the passage of a jet of kindled gas supplying this second center of combustion. This kindled jet of gas, 30 furnished by the incandescent zone of the fuel, not containing any smoke but on the contrary possessing air in excess, is consequently at a very high temperature; its objects are; to produce a suction or draft of 35 the gases and of the outer air, to increase the draft, to produce re-ignition and the complete combustion of the gases and of the smoke conducted by the vacant space surrounding the furnace and raised by this latter to a high temperature.

In the accompanying drawings which are given by way of example only, the invention is shown applied to the furnace of a generator; Figure 1 in longitudinal section, Figs. 45 2 and 3 in cross section on the line A—A and B—B of Fig. 1, Fig. 4 in horizontal section on the line C—C of Fig. 1 and Fig. 5 in vertical section on the line D—D of Fig. 4.

In all the figures similar letters of reference 50 are employed to designate like parts.

In the drawing the grate *a* is comprised between two walls *b* separated by a certain distance from the walls of the furnace in such a manner as to leave free between them and 55 these latter the intervals *c*, freely communicating at the upper part with the furnace.

These intervals *c* communicate by means of bent flues *d* with the chambers *e* situated between the rear wall *i* of the furnace and the fire-bridge. The top of these flues *d* is 60 constituted of refractory slabs overriding one another like the steps of a staircase. Into these chambers *e* also open apertures *f* formed in the rear wall of the furnace and placing in communication the incandescent 65 zone of the fuel with the chambers *e*. These apertures *f* are provided as near as possible to the grate and are inclined as shown in Fig. 1 in order to retain the fuel and prevent the same from falling, at the time of charging, 70 into the chambers *e*. On the other hand the outer air is admitted into each of the intervals *c* through an opening *g* formed in the front wall and is guided by an inclined partition *h* terminating at the entrance to the 75 flues *d*.

The rear wall *i* of the furnace completely insulates the furnace from the rest of the generator, with which this furnace communicates only by way of the apertures *f* and the 80 flues *d*. This rear wall *i* carries a guard *i'* adapted to protect the boilers against the high heat produced by the second center of combustion, and also to prevent the gases of this second center of combustion from 85 imparting too quickly their calories to these boilers. This guard *i'* made of refractory slabs forms the top of the re-ignition chambers.

When the furnace described above is kindled the following phenomena are observable: Upon kindling, the fuel being distributed in a normal layer over the grate, the flames, smoke and the gases escape through the apertures *f* and at the same time through 95 the intervals *c*, the flues *d* and the chambers *e*. When the fuel is well alight, a fresh quantity of fuel is introduced so that the level of this latter comes above the summit of the apertures *f*. This fresh fuel becomes incandescent and the grate is then covered with a height of fuel in a state of ignition extending beyond the summit of the apertures *f*. If a fresh charge of fuel is then supplied, the smoke and gases will be unable to pass 100 through the apertures *f* as these latter are obstructed, so that they must necessarily pass through the intervals *c* and the flues *d* in order to reach the chambers *e*. But at the same time as the draft of the chimney acts 105 directly through the apertures *f* upon the fuel in a state of ignition, there escapes from

these apertures a jet of flame carrying with it a large proportion of the air sucked in by the lower part of the grate, this air having passed through only a small layer of ignited fuel, it follows that the flames issuing through the apertures *f* constitute a gaseous jet which is exceedingly oxidizing, and which may be compared with that of a blow-pipe; its effect is to speedily raise the chambers *e* to a high temperature adapted for combustion.

The smoke and gases issuing at the upper part of the flues *d* mingle together and become intimately mixed with the secondary air which is conducted by the partition *h* to the bottom of the flues *d* and the final mixture thus enters the chambers *e* under the gaseous jets issuing from the orifices *f* in a highly combustible atmosphere and raised to an exceedingly high temperature by the action of these gaseous jets. This mixture of smoke, gases and secondary air is thus obliged to pass upward through the oxidizing gaseous jets, and, in these conditions, the solid carbon which is carried with the hydrocarbons are kindled and completely consumed. Each of these chambers *e* forms a second center of combustion in which all the combustible elements constituting the smoke burn completely. The products of this secondary combustion issue through the apertures *e'* and in order to discharge themselves, follow the ordinary flues comprised in the generator. The action of the second center of combustion having started continues thus indefinitely so long as the furnace is charged with fuel.

The appliance described is applicable to furnaces of all kinds and also to cooking stoves and ranges.

40 The form, dimensions, detail arrangement and the nature of the materials employed will vary in accordance with the various applications.

Claims

45 1. A smoke consuming furnace, having the rear wall of its fire box provided with inclined openings on about a level with the grate, a reignition chamber in rear of the fire box and into which the said openings lead, flues for conveying the gases and smoke from the upper part of the fire box to the reignition chamber below the openings in the rear wall of the fire box, and flues for delivering air to the first named flues at the entrance of said flues 50 to the reignition chamber.

55 2. A smoke-consuming furnace having in its fire box, walls spaced from its side walls and terminating short of the top of said side walls, the front wall of the furnace having 60 openings leading to the spaces between the

said walls and side walls of the heater, the rear wall of the fire box being provided with upwardly and rearwardly inclined openings between the said walls and just above the grate, chambers at the rear of the rear wall of the fire box and into which the openings in the rear wall lead, flues leading from the top of the spaces between the said walls and the side walls of the furnace to the bottom of the said chambers, and partitions in the said spaces and leading from above the openings in the front wall and terminating at the entrance to the said flues, substantially as herein shown and described.

3. A smoke-consuming furnace having on the sides of its fire box spaces communicating with the outer air through openings in the front wall of the furnace, the rear wall of the fire box being provided with inclined openings above the grate, chambers at the rear of the rear wall of the fire box and into which the openings in the rear wall lead, flues leading from the top of the side spaces of the fire box to the bottoms of the said chambers, the tops of the flues being in step form, and means for guiding the air entering the openings in the said spaces to the said flues, substantially as described.

4. A smoke-consuming furnace having on the sides of its fire box spaces communicating with the outer air through openings in the front wall of the furnace, the rear wall of the fire box being provided with openings above the grate, chambers at the rear of the rear wall of the fire box and into which the openings in the rear wall lead, flues leading from the said spaces of the fire box to the chambers, and means for guiding the air entering the said spaces to the said flues, substantially as described.

5. A smoke-consuming furnace, having spaces at the sides of its fire box and having the rear wall of the fire box provided with an upwardly inclined opening, opening into the fire box just above the grate, a reignition chamber at the rear of the fire box and into which the said opening leads, the opening being of a width equal to that of the chamber, flues leading from the top of the said spaces to the bottom of said chamber, and means for supplying air to said flues, substantially as herein shown and described.

The foregoing specification of my improvements relating to apparatus for consuming smoke in stoves and furnaces signed by me this 30th day of September, 1904.

CHARLES JOSEPH ROUX.
